UNITED STATES PATENT OFFICE.

HANS BUTTNER, OF BUFFALO, NEW YORK.

IGNITER.

1,083,272.

Specification of Letters Patent. Patented Jan. 6, 1914.

Application filed December 20, 1911. Serial No. 667,063.

To all whom it may concern:

Be it known that I, HANS BUTTNER, of the city of Buffalo, county of Erie, and State of New York, United States of America, have 5 invented certain new and useful Improvements in Igniters, and do hereby declare that the following is a full, clear, and exact description of the same.

The object of this invention is to provide 10 an improved device of the character set forth comprising a body for containing an inflammable and readily ignitable fluid, such for instance, as alcohol, together with a wick carrying element so mounted that either end 15 thereof may project into or from the body, one end of the wick carrying element bearing an element of the igniting device, which cooperates with another igniting element supported upon the body, as hereinafter set 20 forth.

Further objects and advantages of the invention will be set forth in the detailed description which now follows.

In the accompanying drawing Figure 1 25 is a perspective view of a body member or receptacle hereinafter described. Fig. 2 is a like view from the rear side of said receptacle. Fig. 3 shows in perspective the elements of the wick carrying member, and 30 Fig. 4 is an assembled view of the wick carrying member. Fig. 5 is a cross section of the receptacle. Fig. 6 is an enlarged detail view of the wick tube and assembled parts, partly in cross section and partly in 35 elevation.

Like numerals designate corresponding parts in all of the figures of the drawing.

Referring to the drawing 1 designates a cap externally threaded to adapt it to be 40 screwed into a sleeve 2, see Figs. 3 and 4. The sleeve 2 is internally threaded at 3 and is spanned by a web 7 having an internally threaded opening 8 formed therethrough. A wick tube 10 has externally threaded 45 portions 9 and 11 either of which may engage with the threads of opening 8. One end of the wick tube is split to form resilient gripping members. A wick filling 13 of asbestos or the like, fills the wick tube. 50 A steel plug having a roughened or file like end is embedded in the asbestos at the split end of the wick tube and is retained in position by the gripping members 12. A screen 15 overlies and partially incloses the plug carrying end, said screen aiding in keeping the plug in place. Aluminum nitrid strips 55

16 and 17 are secured to one of the faces of a receptacle 18. This receptacle serves to receive alcohol or a like ignitable fluid and said receptacle is provided with a neck extension 20 externally threaded for the reception of the threads 3 of sleeve 2. A hinged supporting plate 4 is mounted upon the rear side of the receptacle and is provided with an inturned toothed flange 6, 60 which, when plate 4 is swung upwardly, projects outwardly and serves as a supporting means for the receptacle.

When the device is not in use, the wick elements are assembled in the relation shown 70 in Figs. 3 and 4 and the threads 3 at the lower end of sleeve 2 engage with the neck extension 20 of the receptacle 18. At this time the screen and the lower end of the wick tube project into the alcohol and are 75 thoroughly impregnated therewith. If the wick tube be then withdrawn and the roughened end of plug 14 be passed with pressure over the aluminum nitrid strips 16 and 17 a 80 sparking is produced which results in igniting the wick around and through screen 15. This wick or torch may then be used to ignite any other combustible or fuse or the device may be converted into a lamp by 85 engaging threads 11 with threads of opening 8 and reversing the wick tube so that the end thereof carrying threads 9 will be plunged into the alcohol within the receptacle. When this is done, the flame at the screen end of the wick tube will continue to 90 burn, being continuously supplied with alcohol by the wick.

From the foregoing description it will be seen that simple and efficient means are herein provided for accomplishing the objects of the invention, but while the elements shown and described are well adapted to serve the purposes for which they are intended, it is to be understood that the invention is not limited to the precise construction set forth but includes within its purview such changes as may be made within the scope of the appended claim.

Having described my invention, what I claim is:—

A lamp comprising a receptacle, an aluminum-nitrid strip on the wall of said receptacle, a sleeve secured to the mouth of the receptacle and having a web formed with internal screw threads, a tube provided with 100 spaced externally threaded portions, each of said threaded portions being adapted to en-

gage the internally threaded web, a wick carried by each end of the tube, and an igniting element secured to each end of the tube, the tube being securable in said web so that either end thereof will project downwardly into the receptacle to receive inflammable liquid contained therein.

Signed at Buffalo, in the county of Erie,

State of New York, the 22nd day of November, 1911, in the presence of two witnesses.

HANS BUTTNER.
